SWITCH WITH THERMAL OVERLOAD AND INSTANTANEOUS TRIPPING INCORPORATING FUSE MANUAL AND VACUUM SWITCH INTERRUPTING MEANS

Sigurd O. Rodeseike, Greensburg, Pa., and Philip L. Camp, Stonington, Conn., assignors to I-T-E Circuit Breaker Company, Philadelphia, Pa., a corporation of Pennsylvania

Filed Jan. 23, 1964, Ser. No. 339,727
8 Claims. (Cl. 200—114)

The instant invention relates to circuit protective devices and more particularly to protective means for use in relatively high capacity current circuits in the electrical power and distribution field wherein the protective means is comprised of a fused switch having thermal over-load tripping, thereby incorporating current-limiting fuse, thermal, instantaneous magnetic and manual vacuum switch tripping operations in cases of either over-load or severe short-circuit conditions.

In the fused interrupter switch field, present day interrupter switch design is usually normally comprised of a fuse element series connected with an interrupter switch which is so designed as to place the fuse member in series with the circuit being protected. The fuse provides current-limiting characteristics so as to severely limit the large surge currents which may develop during a fault current condition in order to protect the circuit components in series with the fuse member. Such fuses are designed to blow in response to high fault current conditions and simultaneously therewith to limit the let-through current so as to protect the components in the circuit in series connection with the fuse. However, there are no presently available fused interrupter switch arrangements which provide thermal and manual, as well as instantaneous tripping capabilities as well as providing a manual and instantaneous tripping operation without removing the fuse from the series connected circuit and further to provide instantaneous tripping before the fuse has an opportunity to blow so as to provide a wider latitude of protection regardless of the fault current condition which may develop.

The instant invention provides an interrupter switch assembly having a refillable and replaceable current-limiting fuse element combined in series operation with a vacuum switch and mechanical trip means in a single substantially continuous housing arrangement to provide thermal, instantaneous and manual operation of the vacuum switch as well as the circuit protection afforded by the fuse.

The instant invention is comprised of a fuse switch housing assembly divided into a fuse, a mechanism and a vacuum switch compartment with the appearance of the assembly being substantially cylindrical in configuration. The fuse compartment is positioned at the top of the substantially barrel-shaped assembly and is provided with a heat sink and thermal member which is removably clamped to the barrel assembly to provide for ready replacement of the fuse sub-assembly. The positions at the lower end of the fuse compartment are thermal probe means and trigger pin means which extend through the bottom of the fuse compartment into the mechanism compartment.

The mechanism compartment is comprised of a cylindrical metallic housing enclosed in its top and bottom ends by the lower and upper ends of the fuse and vacuum switch compartments respectively. The metallic housing of the mechanism housing compartment is employed as the current carrying means between the fuse and vacuum switch compartments. The mechanism housing contains an operating mechanism mechanically cou-

2

pled to a reciprocally mounted operating plunger which forms part of the vacuum switch. The mechanism compartment further includes trip means controlled by the fuse compartment pin means and bi-metal means controlled by the fuse compartment thermal probe, which trip and bi-metal means are mechanically linked to the operating mechanism. In addition thereto, the mechanism compartment is further provided with instantaneous trip means which operates under the control of the current carried by the vacuum switch to provide instantaneous tripping of the operating mechanism, which under such control acts to rapidly open the vacuum switch means.

The vacuum switch compartment is electrically connected to the conductive housing of the mechanism compartment and contains a vacuum switch, the lower end of which is connected to the lower terminal of the vacuum switch compartment.

The fused interrupter switch assembly may be mounted upon a draw-out type switchgear carriage, such that it is pivoted at its lower terminal and may be mechanically connected and/or disconnected at its upper end to a stationary terminal. The mechanical operating means for moving the assembly into and out of engagement with the stationary disconnect terminal is both mechanically and electrically coupled to the conductive housing of the mechanism compartment and the link therebetween is provided with a lightning arrester assembly. By placing the lightning arrester assembly into the connecting link this electrically connects the arrester between the fuse and the switch means, thus protecting the switch contacts from large current surges.

By suitable adjustment of the instantaneous and thermal tripping mechanisms, it has been found that these mechanisms in combination with a 170 amp fuse, for example, yields protection in a range from zero to approximately 2000 amps before operation of the fuse member. In an application utilizing a 300 amp fuse, protection in the range from 0-9000 amps is obtainable. With such an arrangement it is possible to save the fuse from operating on all except major faults. Further adjustments make it possible to blend the three characteristics, fuse, thermal and instantaneous tripping operations so as to control any given portion of any fuse characteristic in accordance with the needs of the user.

It is therefore one object of the instant invention to provide a fused interrupter switch arrangement incorporating fuse, thermal and instantaneous tripping operations.

Another object of the instant invention is to provide a novel fused interrupter switch arrangement housing a fused, thermal, instantaneous and manual tripping mechanism, and vacuum switch means within a single housing.

Another object of the instant invention is to provide a novel fused interrupter switch arrangement housing a fused, thermal, instantaneous and manual tripping mechanism, and vacuum switch means within a single housing wherein the above three sub-assemblies are arranged in separate compartments within the housing.

Another object of the instant invention is to provide a novel fused interrupter switch arrangement housing a fused, thermal, instantaneous and manual tripping mechanism, and vacuum switch means within a single housing wherein the above three sub-assemblies are arranged in separate compartments within the housing and wherein the fuse element of the assembly is arranged so as to be replaceable.

Still another object of the instant invention is to provide a novel fused interrupter switch assembly having 70 fuse operating mechanism and vacuum switch sub-assemblies arranged in separate compartments within a single

housing wherein the central compartment containing the operating mechanisms is electrically coupled to the upper and lower compartments by its conductive cylindrical housing.

Still another object of the instant invention is to provide a novel fused interrupter switch arrangement having fuse operating mechanism and vacuum switch subassemblies arranged in separate compartments within a single housing wherein the central compartment is coupled to the upper and lower compartments by its conductive cylindrical housing which, in turn, is electrically connected to mechanical operating means for moving the housing into and out of engagement with its cooperating stationary terminals whereby the mechanical operating means is further provided with lightning arrester means in order to protect the vacuum switch contacts from surges during the operation thereof.

These and other objects of the instant invention will become apparent when reading the accompanying description and drawings in which:

FIGURE 1 is a side view of a fused switch designed in accordance with the principles of the instant invention and further showing the use of such a switch assembly in connection with draw-out switchgear.

FIGURE 2 is a side view of the fused switch assembly of FIGURE 1 showing the switch housing in greater detail.

FIGURE 3 is a cross-sectional view of the fused switch assembly of FIGURES 1 and 2.

FIGURE 4 is a cross-sectional view of the fused switch assembly of FIGURE 3 taken along the line 4-4'.

FIGURE 5 is a graph showing the time-current characteristics of the device of FIGURES 1-4.

Referring now to the drawings and particularly to FIGURES 1-4, there is shown therein a fused interrupter switch 100 for use in a draw-out type switchgear assembly 10, see FIGURE 1. The assembly 10 of FIGURE 1 is comprised of a draw-out or roll-out type carriage 11 provided with suitable wheels 12 for rolling the carriage 11 along the floor 13 and into and out of a cooperating compartment (not shown) for receiving the carriage 11. The carriage 11 is provided with a vertical rear wall 14 having upper and lower disconnect terminals 15 and 16 respectively, each being provided with conductive fingers 15a and 16a for making electrical contact with the stationary disconnect terminals (not shown) provided within the compartment employed to house the draw-out assembly 10. A ground shoe 17 is provided at the lower end thereof for the purpose of grounding the carriage 11 when the drawout assembly 10 is in its connected position within the compartment which receives it.

Also mounted upon the vertical rear wall 14 is an auxiliary contact means 18 which is provided for the purpose of giving additional electrical indication of switch position and switch/fuse operation.

The lower disconnect terminal 16 has secured thereto a stationary conductive terminal 19 which projects into the interior of the draw-out carriage housing 20. This conductive terminal 19 is provided with a suitable aperture (not shown) for receiving a pin means 21 to pivotally couple the lower terminal 101 of the fused interrupter switch assembly 100. The upper terminal 102 of assembly 100 makes sliding engagement with a set of draw-out fingers 15b which are coupled to upper disconnect terminal 15. With the arrangement of FIGURE 1 the assembly 100 is designed to pivot about pin 21 so as to bring upper terminal 102 into and out of engagement with the draw-out finger set 15b.

The mechanism of the switch assembly 100 is under control of the operating mechanism 22 positioned at the lower end of assembly 10 and operated by means of a manual charging and operating handle 23 coupled to the operating mechanism 22 and accessible exterior of the door 24 of compartment 20. The operating mechanism 22 is provided with an arm 23 pivoted at 24. The up-

per end of arm 23 is linked at 25 to one end of a connecting link 26 which link 26 is a lightning arrester. The upper end of lightning arrester 26 is linked at 27 to the tripper bar arm 103 of the fused switch assembly 100. The lightning arrester 26 is provided due to the fact that its connection with the switch assembly 100 is made to a hot or live element thus permitting bypass of the lower compartment of the switch assembly 100 during high current surges in a manner to be more fully described.

The draw-out assembly 10 of FIGURE 1 may further be provided with an auxiliary compartment 28 for housing other desired equipment.

FIGURES 2-4 show a fuse switch assembly 100 as being comprised of an upper conductive terminal 102 having a cylindrical conductive base portion 102a which serves the dual function of upper terminal and heat sink. The upper terminal 102 is rigidly clamped by means of a suitable clamping ring 104 to a cylindrical organic and hence insulating tube 105. Tube 105 is threaded at 105a so as to threadedly engage the tapped inner portion 104a of clamp ring 104. The lower end of insulating tube 105 is likewise tapped at 105b so as to threadedly engage a second clamping ring 106 which is tapped along its inner surface 106a for threaded engagement with the lower end 105b of tube 105. The fuse sub-assembly 107 is housed within insulating tube 105 and is comprised of an upper copper diaphragm terminal 108 which makes physical and electrical engagement with the terminal 102. The fuse sub-assembly 107 is further comprised of a porcelain plug 119 about which is wound the main fuse element 110 which is normally wound in a helical manner in the manner shown in FIGURE 3. Immediately adjacent the porcelain plug 109 and positioned longitudinally in cylinder 105 is a trigger wire chamber 111 secured at the upper end thereof to couple diaphragm terminal 108 at the lower end thereof to a housing 112 containing an explosive material or charge 113 for actuating a striker pin 114 which functions in a manner to be more fully described in order to cause the switch mechanism to perform a tripping operation of its vacuum switch. All of these elements are housed within a ceramic former 115 which is a cylindrical tube extending in the vertical direction within the tube 105. The region between ceramic former 115 and insulating cylinder 105 is filled with sliver sand material 116 (see FIGURE 4) which is designed to act as an arc quenching powder. The fuse sub-assembly 107 described herein operates and is designed so as to be substantially similar to the fuse structure described in U.S. Patent 3, 012,121, entitled Electric Fuses, filed by B. C. Hicks, issued December 5, 1961, and assigned to the assignee of the instant invention. For a detailed description of the operation of the fuse sub-assembly the reader's attention is drawn to the above mentioned U.S. patent. For the purpose of understanding the instant invention it is sufficient to understand that the helical wires 110 are designed to melt in a predetermined fashion so as to destroy the current path between the upper and lower copper diaphragms 108 and 116 and at the same time to severely limit the let-through current which is present before this current path is severed. The operation of the trigger assembly is such that the wire element 111, when sufficiently heated due to the current path therethrough acts to ignite the explosive charge in chamber 112 causing the pin 114 to be driven downward in very rapid fashion in order to initiate a tripping operation in a manner to be more fully described.

Immediately below the copper diaphragm terminal 116a is a heat sink and terminal member 117 which is formed of a conductive material substantially the same as the element 102. This heat sink and terminal 117 cooperates with the conductive housing 121 of the mechanism compartment 120 to establish a current path from upper terminal 102 through the fuse sub-assembly 107 and the lower terminal 117 to the conductive mechanism hous-

ing 121. Housing 121 is substantially cylindrical in shape and is provided with an upper flange 122 which is securely clamped beneath the clamp ring 106 in the manner shown. This flange makes engagement with the lower circular periphery of lower terminal 117.

The mechanism compartment or sub-assembly 120 is further comprised of a smaller compartment 123 positioned at the upper end of the mechanism housing 121 and provides the housing means for the trigger pin 114 the lower end of which 114a is positioned immediately adjacent a tripper bar 124 pivoted at 125. Compartment 123 also houses a bimetallic element 126, the lower end of which 126a is positioned immediately adjacent a U-shaped portion 127a of the diaphragm member 127. The bi-metal means 126 is further provided with an adjustable member 128 which projects outside of the conductive housing 121 in order to adjust the bimetal ratings for the desired operation thereof.

The diaphragm 127 is further comprised of a first vertical link 129 and a second horizontal link 130 with link 129 being pivotally connected to diaphragm 127 at 131 and with link 130 being connected to link 129 at 132. The opposite end of link 129 is further pivoted at 132a and diaphragm 127 and link 130 are movable about the pivot points 131 and 132. Their motion is controlled by the over-center operating mechanism 133 which is comprised of a U-shaped stationary member 134 having a spring member 135 secured thereto at one end 136. The opposite end of spring member 135 is secured to the operating handle 103 at 136a. The intermediate portion of spring member 135 is coupled to the knee of a toggle mechanism at 138. The toggle mechanism is comprised of links 139 and 140 coupled to form a knee at 138 and is pivotally linked at 141 and 142 to the diaphragm member 127 and plunger member 151 respectively.

The lower portion of the housing compartment 120 is sealed by a disc-shaped conductive member 144 which makes electrical contact with the lower flange 122a of conductive housing 121 and which is clamped under a clamp ring 145 which rigidly clamps flange 122a and terminal 144 to the insulating housing 152 of the vacuum switch compartment 150. Clamp ring 145 is substantially similar to the clamp rings 104 and 106 described previously and is tapped in a similar manner to threadedly engage the threaded upper portion of the insulating housing 152.

The vacuum switch compartment 150 is sealed at its lower end by a copper terminal 101 which is clamped to the housing 152 by a clamp ring 153 which is substantially similar to clamp rings 104, 106 and 145. The inner surface 101a of copper terminal 101 makes electrical contact with the lower terminal 155 of vacuum switch 154. The upper terminal 156 of vacuum switch 154 makes electrical engagement with the conductive copper disc 144 thus establishing the current path through the vacuum switch compartment 150. The vacuum switch 154 may be any suitable type vacuum switch presently available which is provided with a pair of cooperating contacts (not shown) which are operated into and out of engagement by means of the reciprocating plunger 151. Any typical vacuum bottle can be employed to perform the instantaneous magnetic load break and overload switching of currents up to 3000-4000 amps at zero through approximately 23 kv. These bottles should be able to withstand let-through currents of 20,000-50,000 amps peak. Numerous bottles are presently available to cover this range. Typical bottles which may be employed are the Jennings RH5G or R9G. Such bottles are preferable because loads and strokes of these bottles are such as to make possible an operating mechanism to be used which is small enough to be built within the central portion of the assembly 100.

The instantaneous magnetic trip means is comprised of a circular or toroidal magnetic member 157 secured to the lower face of copper diaphragm 144. The magnetic member 157 cooperates with an instantaneous trip ar-

ture ring 158 positioned immediately above the magnetic member 157.

The vacuum switch 154 which is positioned within the magnetic member 157 acts as a one-turn winding so that when a severe over-load or fault current condition occurs magnetic member 157 becomes heavily magnetized causing the armature ring 158 to be drawn downward toward magnetic member 157. This movement is coupled to the trip member 124 by means of the link 159 to set off the operation of the tripping mechanism contained in the mechanism compartment 120.

The operating mechanism functions in the following manner:

The operating mechanism is set by pushing the spring member 135 to the left through the operating rod 103 in the manner shown by arrow 160. This compresses spring member 135 and also urges the knee 138 of the toggle mechanism to the left of the ends 141 and 142 of the toggle mechanism. This action causes the links 139 and 140 to be almost fully extended so as to push plunger 151 vertically downward and diaphragm 127 vertically upward.

In order to perform the instantaneous tripping operation the severe over-load or fault current condition causes magnet 157 to draw armature 158 downward. This downward vertical motion is imparted to the tripper bar 124 causing it to rotate clockwise so as to move diaphragm 127 from the clockwise direction about its pivot point 131. This causes the pivot connection 141 of the toggle mechanism to move to the left relative to knee 138. This enables the spring member 135 to discharge so as to rapidly urge knee 138 in the direction shown by arrow 161. This movement causes the diaphragm 127 to move very rapidly in the clockwise direction and further causes the link 129 to move very rapidly about its pivot point 132 in the counterclockwise direction. This causes the plunger 151 to move rapidly in the upward vertical direction to disengage the contacts (not shown) of the vacuum switch 154.

The tripping operation under control of the fuse trigger pin occurs when sufficient heat is generated due to the over-load or short-circuit current condition causing the explosive charge 113 to drive pin 114 vertically downward. This downward vertical motion is imparted to tripper lever 124 causing it to move the diaphragm 127 in the same manner as previously described so as to operate vacuum switch 154 to the disengaged position.

The tripping operation under control of the bi-metal occurs during moderate over-load conditions and when the bi-metal 126 is sufficiently heated it is urged vertically downward so that its lower end 126a bears against U-shaped portion 127a of diaphragm 127. This urges pivot point 141 to the left of knee 138 to provide the tripping operation of vacuum switch 154 in the same manner as described above. In cases where it is desired to adjust the bi-metal setting this is performed by adjusting the indicator handle 128 which is accessible at the exterior of the housing assembly 100 as shown in FIGURE 2. The calibrations for the necessary adjustment are provided on the face of the conductive housing compartment at 164.

The instantaneous trip mechanism may likewise be adjusted by means of the instantaneous trip calibrating lever 166 which is likewise accessible at the exterior of the operating mechanism compartment, as shown in FIGURE 2. The calibrations 167 provided on the surface of the housing 121 can best be seen in FIGURE 2 and simplify the setting of the instantaneous mechanism.

The condition of the operating mechanism can be read by the calibrations 168 provided on the face of housing 121 in the manner shown in FIGURE 2.

The fuse sub-assembly 107 is a refillable arrangement which may readily be replaced simply by removing clamp ring 104, terminal 102 and copper diaphragm 108 in order to replace the entire sub-assembly. The use of porcelain

as the core 109 and the silver sand as filler 116 provide outstanding heat transfer characteristics which combine with the organic outside tubing 105 and provides sufficient heat to the thermal device cavity 111 and cavity 119 with the thermal probe 119 providing sufficient heat for operation of the bi-metal 126. The thermal probe performs the overload operation, thus permitting the fuse design to concentrate on producing a relatively flat characteristic to allow thermal and instantaneous tripping to be performed for most conditions while keeping let-through current sufficiently low enough to protect the vacuum bottle contacts (not shown).

The fuse thermal probe 119 is a thermal sensing device which senses the temperature of the fuse and acts to operate the mechanism latch.

The thermal probe is also available for operating relay circuits and remote metering devices in order to continuously monitor a condition of the fused switch. The actual bi-metal 126 employed may be a helical bi-metal element or an expanding rod member which may be employed of high magnitude shock resistance characteristics. The adjustment of the bi-metal can be provided by biasing the twist of the bi-metal. This would change the pick-up of the element but would not change the characteristic to any great degree. Another way of adjusting the bi-metal pick-up is by varying the position of an adjustable heat shield around the bi-metal element which can be placed under control of the calibrating arm 128. Such an arrangement can be devised to either cut-in or out the higher temperatures to change the shape of the thermal curve. As one example, an expanding gas detection means can be used to perform this function. A latched snap action tripping means can be provided for the bi-metal operation thus requiring a mechanical reset. The reset operation, however, can be performed simultaneously with the reset operation of the toggle mechanism 139-140 and operating spring 135. This can be provided for by supplying a link between the operating member 103 and the diaphragm 127 in order to reset the bi-metal device.

With the use of the operating mechanism in the center compartment 120 it is possible to either close or open vacuum switch 154 only after a reset operation has taken place. An indication will be registered directly on the mechanism at 168 as shown in FIGURE 2, however if the fuse 107 has blown, the fuse striker pin will interfere with the reset latch and prevent locking in of the mechanism 120. Thus it will be impossible to close the vacuum switch 154 before the blown fuse assembly 107 has been replaced. In this manner it will readily be seen that the trip ON, OFF and RESET operations are performed by pushing lever 103 up or down so as to traverse the arc 137 in order to initiate the appropriate action.

Although the fuse mechanism handle 103 is "hot" as indicated by the flexure member 169 secured between rod 103 and conductive housing 121, the lightning arrester 26 (see FIGURE 1) protects the switch contacts of vacuum switch 154 from current surges due to the connection of lightning arrester 26 between the fuse chamber 107 and the vacuum switch chamber 150.

FIGURE 5 is a curve showing the limits of melting and total clearing for two fuses which may be employed in the assembly 100. In addition the proposed thermal and instantaneous trip characteristics is shown for 100 amp and 600 amp ratings respectively.

The plot 200 of FIGURE 5 is a plot of current along the x axis against time (in seconds) along the y axis with curve 201 showing the minimum operating time for the instantaneous trip device, curve 202 showing the maximum operating time for the instantaneous trip device, dotted curve 203 showing the minimum operating time for the thermal trip, curve 204 showing the maximum operating time for the thermal trip, curve 205 shows the melting characteristics for the 170 amp fuse, curve 206

shows the total clearing characteristics of the same fuse, curve 207 shows the melting characteristics for the 300 amp fuse and curve 208 shows the total clearing characteristics for the 300 amp fuse.

Considering the 300 amp fuse, it can be seen to be completely protected by the thermal and instantaneous trips from zero to about 9000 amps. The 170 amp fuse is protected from 0-450 amps and from 700 amps to 2000 amps. The 170 amp fuse is unprotected in a range between 450 and 700 amps. However, if the thermal trip device is set to approximately 80% of ratings its characteristic will move toward the left on the graph and its maximum operating limit will move down and blend in with the maximum operating limit of the instantaneous trip at approximately the 700 amp 6 second point 209. Thus complete protection will also be established for the 170 amp fuse from zero to approximately 2000 amps.

As another possibility, if the thermal trip is held constant as shown, but the instantaneous trip is adjusted down to approximately 400 amps, the 170 amp fuse will be protected from zero to approximately 3000 amps. In the manners described herein, it can be seen that in practice it becomes possible to save the fuse from operating on all except major faults. It likewise becomes possible to blend the three characteristics, fuse, thermal, and instantaneous, such as to control any given portion of any given fuse characteristic.

It can therefore be seen that the instant invention provides a fused interrupter switch arrangement which has the capability of fused, thermal, instantaneous and a manual opening by virtue of a fuse operating mechanism and vacuum switch compartment provided therein wherein the vacuum switch compartment is protected against current surges, the fuse sub-assembly is completely replaceable and the central compartment housing is the conductive link between the upper and lower compartments to provide the current surge protection through a lightning arrester. The use of the three devices permits an extremely wide latitude of inter-relationships between the fused, thermal and instantaneous characteristics to prevent the fuse from operating on all but major faults and further provides the complete assembly which may be operated in the same manner as prior art fused interrupter switches, but which has the characteristics not presently obtainable through present day devices.

Although there has been described a preferred embodiment of this novel invention, many variations and modifications will now be apparent to those skilled in the art. Therefore, this invention is to be limited, not by the specific disclosure herein, but only by the appending claims.

What is claimed is:

1. Fused switch means comprising substantially cylindrical housing means divided into first, second and third compartments arranged in tandem fashion; said first compartment being at one end thereof and housing replaceable fuse means comprising a fusible element; heat responsive trigger means having a trigger pin extending into said second compartment; and thermal probe means having a first end thereof extending into said second compartment; said third compartment being at the opposite end of said housing means and housing vacuum switch means; said vacuum switch means having a reciprocally mounted plunger means extending into said second compartment; annular magnetic means surrounding said vacuum switch means and positioned in close proximity to said second compartment; said second compartment being intermediate said first and third compartments and housing operating means; said operating means comprising annular armature means positioned in close proximity to said annular magnetic means; a pivotally mounted tripper bar mechanically linked to said armature; said trigger pin means positioned in close proximity to said tripper bar; said trigger pin means being responsive to current of a predetermined magnitude for rotating said tripper bar; bimetal means associated with said thermal

probe means; movable diaphragm means connected to said bimetal means and said tripper bar means; an operating mechanism comprising a toggle mechanism having a first and second end and a knee pivot; said toggle means first end connected to said diaphragm means; said toggle means second end connected to said plunger means; spring means having a stationary first end; said knee pivot being connected to said spring means intermediate the ends thereof; operating lever means connected to the second end of said spring means and movable in a first direction to charge said spring means; said toggle means being moved to an extended position when said spring means is charged to close said vacuum switch means; said diaphragm being movable under control of either said tripper bar or said bimetal means to release said charged spring means; causing said toggle means to collapse; said vacuum switch being opened when said toggle means collapses.

2. Fused switch means comprising substantially cylindrical housing means divided into first, second and third compartments arranged in tandem fashion; said first compartment being at one end thereof and housing replaceable fuse means comprising a fusible element; heat responsive trigger means having a trigger pin extending into said second compartment; and thermal probe means having a first end thereof extending into said second compartment; said third compartment being at the opposite end of said housing means and housing vacuum switch means; said vacuum switch means having a reciprocally mounted plunger means extending into said second compartment; annular magnetic means surrounding said vacuum switch means and positioned in close proximity to said second compartment; said second compartment being intermediate said first and third compartments and housing operating means; said operating means comprising annular armature means positioned in close proximity to said annular magnetic means; a pivotally mounted tripper bar mechanically linked to said armature; said trigger pin means positioned in close proximity to said tripper bar said trigger pin means being responsive to current of a predetermined magnitude for rotating said tripper bar; bimetal means associated with said thermal probe means; movable diaphragm means connected to said bimetal means and said tripper bar means; an operating mechanism comprising a toggle mechanism having a first and second end and a knee pivot; said toggle means first end connected to said diaphragm means; said toggle means second end connected to said plunger means; spring means having a stationary first end; said knee pivot being connected to said spring means intermediate the ends thereof; operating lever means connected to the second end of said spring means and movable in a first direction to charge said spring means; said toggle means being moved to an extended position when said spring means is charged to close said vacuum switch means; said diaphragm being movable under control of either said tripper bar or said bimetal means to release said charged spring means; causing said toggle means to collapse; said vacuum switch being opened when said toggle means collapses; said second compartment having a metallic cylindrical housing having a first end thereof electrically connected to said fuse means and a second end electrically connected to said vacuum switch means; said metallic housing containing said operating means; said operating lever being electrically connected to said metallic housing; lightning arrester means electrically connected between said operating lever and ground potential to protect said vacuum switch from current surges.

3. Fused switch means comprising substantially cylindrical housing means divided into first, second and third compartments arranged in tandem fashion; said first compartment being at one end thereof and housing replaceable fuse means comprising a fusible element; heat responsive trigger means having a trigger pin extending into said second compartment; and thermal probe means having a first end thereof extending into said second compartment; said third compartment being at the opposite end of said housing means and housing vacuum switch

means; said vacuum switch means having a reciprocally mounted plunger means extending into said second compartment; annular magnetic means surrounding said vacuum switch means and positioned in close proximity to said second compartment; said second compartment being intermediate said first and third compartments and housing operating means; said operating means comprising annular armature means positioned in close proximity to said annular magnetic means; a pivotally mounted tripper bar mechanically linked to said armature; said trigger pin means positioned in close proximity to said tripper bar said trigger pin means being responsive to current of a predetermined magnitude for rotating said tripper bar; bimetal means associated with said thermal probe means; movable diaphragm means connected to said bimetal means and said tripper bar means; an operating mechanism comprising a toggle mechanism having a first and second end and a knee pivot; said toggle means first end connected to said diaphragm means; said toggle means second end connected to said plunger means; spring means having a stationary first end; said knee pivot being connected to said spring means intermediate the ends thereof; operating lever means connected to the second end of said spring means and movable in a first direction to charge said spring means; said toggle means being moved to an extended position when said spring means is charged to close said vacuum switch means; said diaphragm being movable under control of either said tripper bar or said bimetal means to release said charged spring means causing said toggle means to collapse; said vacuum switch being opened when said toggle means collapses; said second compartment having a metallic cylindrical housing having a first end thereof electrically connected to said fuse means and a second end electrically connected to said vacuum switch means; said metallic housing containing said operating means; said operating lever being electrically connected to said metallic housing; lightning arrester means electrically connected between said operating lever and ground potential to protect said vacuum switch from current surges.

4. Fused switch means comprising substantially cylindrical housing means divided into first, second and third compartments arranged in tandem fashion; said first compartment being at one end thereof and housing replaceable fuse means comprising a fusible element; heat responsive trigger means having a trigger pin extending into said second compartment; and thermal probe means having a first end thereof extending into said second compartment; said third compartment being at the opposite end of said housing means and housing vacuum switch means; said vacuum switch means having a reciprocally mounted plunger means extending into said second compartment; annular magnetic means surrounding said vacuum switch means and positioned in close proximity to said second compartment; said second compartment being intermediate said first and third compartments and housing operating means; said operating means comprising annular armature means positioned in close proximity to said annular magnetic means; a pivotally mounted tripper bar mechanically linked to said armature; said trigger pin means positioned in close proximity to said tripper bar said trigger pin means being responsive to current of a predetermined magnitude for rotating said tripper bar; bimetal means associated with said thermal probe means; movable diaphragm means connected to said bimetal means and said tripper bar means; an operating mechanism comprising a toggle mechanism having a first and second end and a knee pivot; said toggle means first end connected to said diaphragm means; said toggle means second end connected to said plunger means; spring means having a stationary first end; said knee pivot being connected to said spring means intermediate the ends thereof; operating lever means connected to the second end of said spring means and movable in a first direction to charge said spring means;

said toggle means being moved to an extended position when said spring means is charged to close said vacuum switch means; said diaphragm being movable under control of either said tripper bar or said bimetal means to release said charged spring means causing said toggle means to collapse; said vacuum switch being opened when said toggle means collapses; said second compartment having a metallic cylindrical housing having a first end thereof electrically connected to said fuse means and a second end electrically connected to said vacuum switch means; said metallic housing containing said operating means; said operating lever being electrically connected to said metallic housing; lightning arrester means electrically connected between said operating lever and ground potential to protect said vacuum switch from current surges; said bimetal means and said magnetic member being designed to operate to prevent said fuse means from blowing under all conditions but severe fault current conditions.

5. Fused switch means comprising substantially cylindrical housing means divided into first, second and third compartments arranged in tandem fashion; said first compartment being at one end thereof and housing replaceable fuse means comprising a fusible element; heat responsive trigger means having a trigger pin extending into said second compartment; and thermal probe means having a first end thereof extending into said second compartment; said third compartment being at the opposite end of said housing means and housing vacuum switch means; said vacuum switch means having a reciprocally mounted plunger means extending into said second compartment; annular magnetic means surrounding said vacuum switch means and positioned in close proximity to said second compartment; said second compartment being intermediate said first and third compartments and housing operating means; said operating means comprising annular armature means positioned in close proximity to said annular magnetic means; a pivotally mounted tripper bar mechanically linked to said armature; said trigger pin means positioned in close proximity to said tripper bar; bimetal means associated with said thermal probe means; movable diaphragm means connected to said bimetal means and said tripper bar means; an operating mechanism comprising a toggle mechanism having a first and second end and a knee pivot; said toggle means first end connected to said diaphragm means; said toggle means second end connected to said plunger means; spring means having a stationary first end; said knee pivot being connected to said spring means intermediate the ends thereof; operating lever means connected to the second end of said spring means and movable in a first direction to charge said spring means; said toggle means being moved to an extended position when said spring means is charged to close said vacuum switch means; said diaphragm being movable under control of either said tripper bar or said bimetal means to release said charged spring means; causing said toggle means to collapse; said vacuum switch being opened when said toggle means collapses; said housing assembly having first and second electrode terminals at opposite ends thereof; drawout switch-gear carriage means having upper and lower electrode terminals, said fuse assembly second electrode being pivotally connected to said lower terminal; said fused switch assembly first electrode releasably engaging said upper terminal; second operating means for moving said fused switch assembly first terminal into and out of engagement with said upper terminal; said second operating means being mechanically and electrically linked to said operating lever.

6. Fused switch means comprising substantially cylindrical housing means divided into first, second and third compartments arranged in tandem fashion; said first compartment being at one end thereof and housing replaceable fuse means comprising a fusible element; heat responsive trigger means having a trigger pin extending into said second compartment; and thermal probe means having a first end thereof extending into said second compartment;

partment; said third compartment being at the opposite end of said housing means and housing vacuum switch means; said vacuum switch means having a reciprocally mounted plunger means extending into said second compartment; annular magnetic means surrounding said vacuum switch means and positioned in close proximity to said second compartment; said second compartment being intermediate said first and third compartments and housing operating means; said operating means comprising annular armature means positioned in close proximity to said annular magnetic means; a pivotally mounted tripper bar mechanically linked to said armature; said trigger pin means positioned in close proximity to said tripper bar; said trigger pin means being responsive to current of a predetermined magnitude for rotating said tripper bar; bimetal means associated with said thermal probe means; movable diaphragm means connected to said bimetal means and said tripper bar means; an operating mechanism comprising a toggle mechanism having a first and second end and a knee pivot; said toggle means first end connected to said diaphragm means; said toggle means second end connected to said plunger means; spring means having a stationary first end; said knee pivot being connected to said spring means intermediate the ends thereof; operating lever means connected to the second end of said spring means and movable in a first direction to charge said spring means; said toggle means being moved to an extended position when said spring means is charged to close said vacuum switch means; said diaphragm being movable under control of either said tripper bar or said bimetal means to release said charged spring means; causing said toggle means to collapse; said vacuum switch being opened when said toggle means collapses; said housing assembly having first and second electrode terminals at opposite ends thereof; drawout switch-gear carriage means having upper and lower electrode terminals, said fuse assembly second electrode being pivotally connected to said lower terminal; said fused switch assembly first electrode releasably engaging said upper terminal; second operating means for moving said fused switch assembly first terminal into and out of engagement with said upper terminal; said second operating means being mechanically and electrically linked to said operating lever.

7. Fused switch means comprising substantially cylindrical housing means divided into first, second and third compartments arranged in tandem fashion; said first compartment being at one end thereof and housing replaceable fuse means comprising a fusible element; heat responsive trigger means having a trigger pin extending into said second compartment; and thermal probe means having a first end thereof extending into said second compartment; said third compartment being at the opposite end of said housing means and housing vacuum switch means; said vacuum switch means having a reciprocally mounted plunger means extending into said second compartment; annular magnetic means surrounding said vacuum switch means and positioned in close proximity to said second compartment; said second compartment being intermediate said first and third compartments and housing operating means; said operating means comprising annular armature means positioned in close proximity to said annular magnetic means; a pivotally mounted tripper bar mechanically linked to said armature; said trigger pin means positioned in close proximity to said tripper bar; said trigger pin means being responsive to current of a predetermined magnitude for rotating said tripper bar; bimetal means associated with said thermal probe means; movable diaphragm means connected to said bimetal means and said tripper bar means; an operating mechanism comprising a toggle mechanism having a first and second end and a knee pivot; said toggle means first end connected to said diaphragm means; said toggle means second end connected to said plunger means; spring means having a stationary first end; said

knee pivot being connected to said spring means intermediate the ends thereof; operating lever means connected to the second end of said spring means and movable in a first direction to charge said spring means; said toggle means being moved to an extended position when said spring means is charged to close said vacuum switch means; said diaphragm being movable under control of either said tripper bar or said bimetal means to release said charged spring means causing said toggle means to collapse; said vacuum switch being opened when said toggle means collapses; said second compartment having a metallic cylindrical housing having a first end thereof electrically connected to said fuse means and a second end electrically connected to said vacuum switch means; said metallic housing containing said operating means; said operating lever being electrically connected to said metallic housing; lightning arrester means electrically connected between said operating lever and ground potential to protect said vacuum switch from current surges; said housing assembly having first and second electrode terminals at opposite ends thereof; drawout switch-gear carriage means having upper and lower electrode terminals said fuse assembly second electrode being pivotally connected to said lower terminal; said fused switch assembly first electrode releaseably engaging said upper terminal.

8. Fused switch means comprising substantially cylindrical housing means divided into first, second and third compartments arranged in tandem fashion; said first compartment being at one end thereof and housing replaceable fuse means comprising a fusible element; heat responsive trigger means having a trigger pin extending into said second compartment; and thermal probe means having a first end thereof extending into said second compartment; said third compartment being at the opposite end of said housing means and housing vacuum switch means; said vacuum switch means having a reciprocally mounted plunger means extending into said second compartment; annular magnetic means surrounding said vacuum switch means and positioned in close proximity to said second compartment; said second compartment being intermediate said first and third compartments and housing operating means; said operating means comprising annular armature means positioned in close proximity to said annular magnetic means; a pivotally

mounted tripper bar mechanically linked to said armature; said trigger pin means positioned in close proximity to said tripper bar; said trigger pin means being responsive to current of a predetermined magnitude for rotating said tripper bar; bimetal means associated with said thermal probe means; movable diaphragm means connected to said bimetal means and said tripper bar means; an operating mechanism comprising a toggle mechanism having a first and second end and a knee pivot; said toggle means first end connected to said diaphragm means; said toggle means second end connected to said plunger means; spring means having a stationary first end; said knee pivot being connected to said spring means intermediate the ends thereof; operating lever means connected to the second end of said spring means and movable in a first direction to charge said spring means; said toggle means being moved to an extended position when said spring means is charged to close said vacuum switch means; said diaphragm being movable under control of either said tripper bar or said bimetal means to release said charged spring means causing said toggle means to collapse; said vacuum switch being opened when said toggle means collapses; said second compartment having a metallic cylindrical housing having a first end thereof electrically connected to said fuse means and a second end electrically connected to said vacuum switch means; said metallic housing containing said operating means; said operating lever being electrically connected to said metallic housing; lightning arrester means electrically connected between said operating lever and ground potential to protect said vacuum switch from current surges; said housing assembly having first and second electrode terminals at opposite ends thereof; drawout switch-gear carriage means having upper and lower electrode terminals said fuse assembly second electrode being pivotally connected to said lower terminal; said fused switch assembly first electrode releaseably engaging said upper terminal; second operating means for moving said fused switch assembly first terminal into and out of engagement with said upper terminal; said second operating means being mechanically and electrically linked to said lightning arrester means.
